UNITED STATES PATENT OFFICE.

AUGUSTE FRAYSSÉ, OF ANTWERP, BELGIUM.

MACHINE FOR CLEANING WOOL.

SPECIFICATION forming part of Letters Patent No. 292,295, dated January 22, 1884.

Application filed January 29, 1883. (No model.) Patented in Belgium July 21, 1882, No. 58,538; November 24, 1882, No. 59,653, and March 28, 1883, No. 60,892; in France July 24, 1882, No. 150,919; in England August 2, 1882, No. 3,675; in Germany September 6, 1882, No. 21,582; in Austria-Hungary September 18, 1882, No. 41,904 and No. 10,122; in Italy November 30, 1882, No. 14,849; in Victoria January 11, 1883, No. 3,478; in Spain April 13, 1883; in Cape of Good Hope May 22, 1883, No. 243; in South Australia May 26, 1883, No. 360; in Natal May 29, 1883, No. 5,024; in Queensland August 13, 1883, No. 526, and in New South Wales August 14, 1883.

To all whom it may concern:

Be it known that I, AUGUSTE FRAYSSÉ, a resident of Antwerp, Belgium, and a subject of the King of the Belgians, have invented certain Improvements in Machines for Cleaning Wool, of which the following is a specification.

My invention consists of an improved machine for thoroughly cleaning wool either unwashed or partially washed and removing from it all thistles, burrs, and other impurities in the fleece, partially combing out the latter and preparing it for a thorough washing and perfect carding, as more fully described herein-after.

15 In the accompanying drawings, Figure 1 is a side view of the machine; Fig. 2, a longitudinal section thereof. Fig. 3 is a plan view, partially in section; and Fig. 4, a transverse section on the lines *y y*, Fig. 1.

20 Between the side frames, *A A*, of the machine is mounted a tank, *O O*, for the reception of the water and the refuse removed from the wool by the cleaning-cylinders and water-jets from the pipes mounted above it.

25 *B* is an endless feed-apron passing over rollers *b* and *b'*, the former being mounted in bearings in the side frames, while the roller *b'* is mounted in bearings in extensions *a a*, adjustable horizontally on the side frames, to permit the slack of the apron to be taken up. 30 Rotary motion is imparted to the roller *b* to traverse the feed-apron in direction of the arrow, Fig. 2, as hereinafter described, and adjacent to the delivery end of the apron are arranged two toothed feed-rolls, *C C'*, mounted in suitable bearings in the frame, and rotated in the directions of the arrows, Figs. 1 and 2.

35 *D* is a cylinder covered with card teeth or needles, according to the character of the wool to be treated. This cylinder is mounted in bearings in the frame and is rotated more rapidly than the feed-rolls in the direction of the arrow, Fig. 2. Above this cylinder is mounted a doffer-cylinder, *E*, provided on its periphery with longitudinal blades and rotated in the direction of the arrow at a high speed—say a

thousand revolutions a minute—and back of this doffer-cylinder is a trough, *S*, for the reception of the burrs and waste removed by the doffer from the cylinder *D*. A second cylinder, *G*, similar in all respects to the cylinder *D*, except that it has finer teeth, and provided, like the cylinder *D*, with a doffer-cylinder, *E'*, and its receiving-trough *S'*, is also mounted in bearings in the frame to rotate in the direction of the arrow, Fig. 2. Between these two cylinders is an intermediate toothed drum, *F*, also mounted to turn in bearings in the frame in the direction of its arrow, and transfer the fibers from the cylinder *D* to the cylinder *G*. 50 On the side of the cylinder *G*, opposite the drum *F*, is a rotary brush or doffer, *H*, which, revolving at a high speed, throws the fibers from the cylinder *G* into the water in the tank *O*, where the impurities settle down in the tank, 55 the sand and finer impurities passing through the perforated false bottom *P*. These may be drawn off with the water by opening the cock *x* in the bottom of the tank. At the end of the tank is an overflow, *O'*, and immediately 60 below this is a sieve-like cleaner or strainer, *N*. This consists of a frame, of a hexagonal shape in the present instance, as shown in Fig. 3, mounted to turn on a central vertical pivot, *n*, on brackets projecting from the end of the 65 tank, so that any one of its sections or segments may be brought opposite the overflow *O'*. Each section of this frame has a series of parallel bars, *n'*, about a millimeter and a-half apart, and each bar carries one or two rows of 70 upwardly-projecting wires or blunt needles. 75 Immediately below the section of the sieve *N*, which is opposite the overflow, is a frame, *I*, secured to the end of the tank, and carrying a series of horizontal fluted rollers, *i*, gearing into each other. These rollers are mounted in small square bearings, fitted in horizontal slots in the side frames, *I*, and pressed into contact with each other to keep the rollers *i* in gear by means of springs *i'*, Fig. 2. The 80 journal of one of these rollers is extended some distance beyond one of its bearing-

85

blocks, and is provided with a small pulley, j , by which rotary motion may be imparted to it to drive these rollers.

Immediately over the junction of the feed-
5 rollers C C' with the cylinder D is arranged a slotted tube, R, Fig. 2, which throws a sheet or stream of water for a purpose described hereinafter. A similar slotted water-tube, R', throws a stream of water onto the edge of the cylinder D, at a point just in advance of its junction with the drum F. At the points of junction of the drum F and cylinder G, and of the latter with the brush H, are similar water-pipes, R² and R³, respectively. A per-
15 forated water-pipe, R⁴, is also arranged over the sieve N and roller-frame I, to throw streams of water thereon.

The operation is as follows: The wool, which may be unwashed or may have been partially
20 washed, is laid on and spread out over the feed-apron B, which carries it to the feed-rolls C C'. The latter feed it to the cylinder D, which revolves in the direction of the arrow, and the sheet of water projected from the pipe
25 R, in a direction opposite that in which the teeth of the cylinder point, forces the wool down between the said teeth and spikes the burrs and impurities thereon, and these latter in turn are thrown off the cylinder D by the
30 rapidly-revolving doffer E into the receiving-trough S. When the wool, carried round by the cylinder D, comes nearly to the point of junction with the toothed drum F, the sheet of water projected from the slotted pipe R' removes or loosens the fibers from the teeth of the cylinder D, so that they are taken by the drum F. The fibres are transferred from the latter to the cylinder G, and the burrs and lumps not already removed are spiked on the
35 teeth of this cylinder by the sheet of water from the pipe R², and are thence thrown by the doffer E' into the trough S'. The stream of water from the pipe R³ loosens the fibers from the teeth of the cylinder G, so that the
40 said fibers are thrown by the rapidly-revolving brush H into the water in the tank O. The fibers then float off at the overflow O' onto the spiked frame N, and are there forced down among the needles and the fluted rollers
45 i i by the streams of water from the pipe R⁴. These rollers draw the fibers rapidly through and feed them into a suitable receptacle. In the passage of the wool through this sieve, any burrs or lumps which have not already
50 been removed will be left on the points of the needles or between the bars, from which they may be removed by a brush or other suitable means.

In some cases the second cylinder, G, with
60 its doffer E', trough S', pipes R² and R³, and the intermediate drum, F, may be dispensed with, and in such case the brush H will be arranged adjacent to the cylinder D, instead of the cylinder G, as will be readily understood.

Although I do not confine myself to any particular means of operating or driving the

movable parts of the machine which I have described above, I have illustrated and will now describe an arrangement of gearing which
70 may be employed for the purpose.

Motion is imparted to the shaft F' of the drum F by a belt passing over a pulley, v, and at the opposite end of the shaft is a pinion, 1, gearing into a spur-wheel, 2, Fig. 4, mounted
75 on a stud, 3, on the frame. Formed in one piece with this spur-wheel is a pulley, 4, over which passes a belt to a pulley, 5, on the axis of the cylinder D. The opposite end of this axis is provided with a pair of pulleys, 6 7, 80 Fig. 3, over one of which passes a belt to the pulley 8 on the end of the axis of the cylinder G, Fig. 1. The second pulley, 7, transmits motion by a belt to a pulley, 9, on a counter-shaft, K, which in turn transmits motion to 85 the apron B by a belt passing over a pulley, 10, and a pulley, 11, on the roller b. The feed-rollers C C' receive their motion from the roller b through gearing 12, 13, and 14, Fig.
90 3, at the opposite side of the machine. The doffers E E' and brush H receive their motion from a counter-shaft, K', which is driven by a belt from a pulley, v', on the shaft F', Fig. 1. A belt, passing over a pulley, 15, Figs. 2 and 3, on the end of the shaft K', transmits motion 95 to a small pulley, 16, on the shaft of the doffer E', Fig. 3, and the doffer E is driven from the latter by means of a crossed belt, Fig. 1. A belt from the pulley 17 on the counter-shaft K' transmits motion to a pulley, 18, on the brush 100 H, and motion is transmitted from this same shaft K' to the pulley j, through belts and pulleys 19, Fig. 1.

I claim as my invention—

1. Two toothed cylinders and mechanism 105 for rotating the same with their teeth in contact, in combination with a water-pipe adjacent to the point of junction of the two cylinders, and adapted to project a stream of water at that point to assist in the transfer of the fibers from the teeth of one cylinder to those of the other, all substantially as set forth.

2. The combination of a frame having projecting teeth, and devices for feeding wool or other fibers thereto, with a pipe adapted to project a stream of water onto the teeth in a direction opposite to that in which they point, whereby the lumps in the wool will be spiked on the teeth and the fibers forced down between the teeth, all substantially as described.

3. The combination of feed-rolls and a toothed cylinder, D, with a pipe, R, adapted to force a stream of water onto the cylinder D against the points of its teeth, a doffer-cylinder, and mechanism for operating the cylinders and rolls, substantially as specified.

4. The combination of feed-rolls and a toothed cylinder, D, with a slotted pipe, R, a doffer-cylinder, E, a pipe, R', a roll or drum 130 to take off the fibers from the cylinder D, and mechanism for operating the cylinders and rolls, substantially as described.

5. The combination of a frame of spaced

bars, each having projecting teeth, with a pipe adapted to throw streams of water against the points of said teeth, as set forth.

6. The combination of a frame of spaced bars, each having projecting teeth, and a pipe adapted to throw streams of water against the points of said teeth, with devices for feeding wool or other fibers onto said frame, and rollers, and mechanism for operating the same,

to withdraw the fibers from between the bars, substantially as described.

In testimony whereof I have signed my name to this specification in the presence of two subscribing witnesses.

AUGTE. FRAYSSÉ.
